Primary Examiner — Elizabeth J Oswecki(74) *Attorney, Agent, or Firm* — Knobbe Martens Olson
& Bear LLP(57) **CLAIM**

The ornamental design for a parcel locker, as shown and described.

DESCRIPTION

FIG. 1 is a perspective view of a parcel locker showing our new design.

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view of thereof.

Broken lines are used to illustrate features which form no part of the claimed design.

1 Claim, 5 Drawing Sheets(56)
